UNITED STATES PATENT OFFICE.

FRANKLIN CHARLES NICKEL, JOHN EDGAR MARTIN, AND CHARLES EDMUND BLACKBURN, OF JACKSONVILLE, ILLINOIS.

ELECTRIC GAS-IGNITER.

No. 852,342.

Specification of Letters Patent.

Patented April 30, 1907.

Application filed February 6, 1906. Serial No. 299,739.

To all whom it may concern:

Be it known that we, FRANKLIN CHARLES NICKEL, JOHN EDGAR MARTIN, and CHARLES EDMUND BLACKBURN, citizens of the United States, residing at Jacksonville, in the county of Morgan and State of Illinois, have invented certain new and useful Improvements in Electric Gas-Igniters; and we do hereby declare the following to be a full, clear, and exact description of the invention, such as will enable others skilled in the art to which it appertains to make and use the same.

Our invention relates to electrical gas lighters and its object is to provide a device of this character which can be readily connected to a burner and which is positively operated when the valve is turned to allow the gas to escape from the burner.

A still further object is to provide a novel form of contact which is secured to the burner in a peculiar manner, the same having a novel arrangement of insulation and capable of being taken off without disturbing any of the other portions of the burner or igniter.

With the above and other objects in view the invention consists of a bracket adapted to be clamped permanently upon the fixture by the burner and this bracket has a clip detachably secured to it, insulation being interposed between the clip and the bracket. A coil spring is connected in a novel manner to the clip and has a stem projecting upward from it in close proximity to the tip of the burner and this stem constitutes one of the contacts of the igniter.

The button of the valve has a stem projecting from it and overlapping the stem of the spring and whenever the button is rotated so as to turn on the gas the two stems will be brought into contact and then separated to produce a spark close to the tip.

It is of course understood that the clip and the fixture are connected to opposite poles of a generator.

The invention also consists in further novel construction and combination of parts hereinafter more fully described and claimed.

In the accompanying drawings we have shown the preferred form of our invention, and in said drawings—Figure 1 is a perspective view of a fixture having our improved igniter connected thereto. Fig. 2 is a detail view of the bracket detached. Fig. 3 is a

similar view of the spring contact, and Fig. 4 is a perspective view of the clip.

Referring to the figures by numerals of reference, 1 is that portion of a fixture constituting a valve casing and a valve 2 is rotatably mounted therein and has a button 3 which may be of any suitable form and which has a stem 4 projecting from it, said stem terminating in a lateral extension 5 which is adapted to move in an arc over a tip 6 located in the upper end of a burner 7. This burner is of the ordinary variety and is adapted to clamp upon the lower apertured end 8 of an L-shaped bracket 9, thereby securing said bracket upon the fixture 1. A strip 10 of insulation is placed around the upper end of bracket 9 and bearing upon this insulating material is a U-shaped clip 11 having apertures 12 in its ends for the reception of a clamping screw 13, which also acts as a binding post whereby one wire of a circuit can be connected thereto. A tongue 14 projects upward from the central portion of the clip and a downwardly-extending curved tongue 15 is also disposed centrally on said clip. Tongue 14 is adapted to project into a coiled spring 16 while the lower tongue 15 engages a hook 17, which is formed integral with the lower end of the spring. Said spring is therefore maintained at all times in position upon the clip and cannot be accidentally displaced. The upper end of the spring terminates in a stem 18, which projects slightly above the upper end of the tip 6 and into the path of the lateral extension 5 of stem 4.

It will of course be understood that this attachment is to be connected to a source of electricity in the usual manner, one wire being fastened to clip 11, while the other conducts the current directly to the fixture 1 and the parts electrically connected thereto. When the gas is shut off the button 3 assumes a substantially horizontal position as ordinarily, as does also the stem 4, which is connected thereto.

When it is desired to ignite the gas the button is turned and will cause stem 4 to swing upward in the direction of the arrow shown in Fig. 1 until its extension 5 comes into contact with the stem 18. A circuit will be immediately established between the two stems and as the swinging movement of the extension 5 continues a spring

stem 18 will slip longitudinally along the extension 5 and also downward in relation thereto until the contact is finally broken, whereupon a spark will be produced. The two stems are so located in relation to each other that this spark will be formed directly opposite the center of the tip 6 and the sliding or sweeping movement of stem 18 on the extension 5 serves to throw the spark toward the tip thereby further insuring the ignition of the gas. It will be seen that this igniter is very simple in construction and does not have any parts which can easily get out of order. Moreover the attachment can be used in connection with any forms of tips and can be easily used with a globe. To shut off the gas the operation above described is reversed.

What we claim is -

- 20 1. An igniter comprising a valve, an angular stem movable therewith, a bracket, a clip mounted upon and insulated from the bracket, said clip having oppositely-extending tongues, a coil seated upon one of the tongues, a hook integral with the coil and engaging the other tongue and a resilient stem projecting from the coil into the path of the first mentioned stem.
- 25 2. In an igniter, the combination with an angular bracket adapted to be secured to a fixture; of a clip mounted upon and insulated from the bracket and having integral oppositely-extending tongues, a coil mounted on one of the tongues, a hook integral with the

coil and engaging the other tongue and a resilient contact projecting from the coil. 35

3. The combination with a fixture having a burner thereon; of an angular bracket clamped upon the fixture by the burner, a clip secured to the upper end of said bracket 40 a valve, a stem projecting from the valve, oppositely-extending tongues integral with the clip, a coil mounted on one of the tongues, a hook integral with the coil and engaging the other tongue and a resilient contact extending from the coil into the path of the stem. 45

4. The combination with a fixture having a burner thereon; of an L-shaped bracket clamped upon the fixture by the burner, a 50 U-shaped clip secured to and insulated from the upper end of said bracket, oppositely extending tongues integral with said clip, a coil mounted on one of the tongues, a hook integral with the coil and engaging the other 55 tongue, a resilient contact extending from the coil, a valve, a stem projecting from the valve and into the path of said resilient contact.

In testimony whereof we have signed our 60 names to this specification in the presence of two subscribing witnesses.
